(57) **CLAIM**

The ornamental design for a ballpoint pen, as shown and described.

DESCRIPTION

1. Ball-point pen
- 1.1 is a left side elevational view of the ballpoint pen showing my new design;
- 1.2 is a front elevational view thereof;
- 1.3 is a right side elevational view thereof;
- 1.4 is a rear elevational view thereof;
- 1.5 is a top plan view thereof;
- 1.6 is a bottom plan view thereof;
- 1.7 is a first perspective view thereof; and
- 1.8 is a second perspective view thereof rotated 90 degrees from the preceding view.
